JULIUS DORNETH, OF BERLIN-KONRADSHOHE, GERMANY, ASSIGNOR TO THE FIRM
TYPOGRAPH-GESELLSCHAFT M. B. H., OF BERLIN, GERMANY

MATRIX-SETTING AND TYPE-LINE-CASTING MACHINE

Application filed April 23, 1929, Serial No. 357,480, and in Germany November 13, 1928.

In matrix setting and type casting machines with ring spacers, the latter have a given diameter so that in the case of the usual heights of line, they close the casting 5 slot of the casting mold as indicated in Figure 3 of the accompanying drawing. If however particularly high lines are to be cast, these space rings are not sufficient, as a tight closing can be obtained with them only 10 if they are advanced to the extent a as indicated in Figure 4 of the accompanying drawing. This is however not possible in existing machines. In such cases special straight spacers therefore are used which 15 have to be inserted by hand.

According to this invention the square spindle which carries the space rings is resiliently mounted, and thus it is possible to use the ordinary ring spaces contained in the 20 machine, for any height of line. The result of this mounting by means of springs is that the space rings automatically assume the positions shown in Figures 3 and 4, as well as any intermediate positions that may be re- 25 quired.

A construction according to the invention is illustrated in the accompanying drawing, applied to a machine in which two space rings are mounted one above the other on a 30 bar suspended to a guide wire.

Figure 1 is a cross section.

Figure 2 is a plan.

Fig. 3 is a fragmentary elevational detail partly in section showing the position as- 35 sumed by the ring.

Fig. 4 is a similar view showing the same parts in another position.

Two space rings b are arranged one above the other on a bar c and are held in the setting 40 position by square spindles d which are mounted at both ends in supports e, f . The supports are provided with guide blocks g which are adjustably mounted in guides h by means of a pin h^1 and slot h^2 .

45 The blocks g and therefore the square spindles are always held by means of springs i in such a position that the space rings can freely run on to them the said rings being then in the position advanced (in Figure 4) 50 to the extent a , so that a tight closing is en-

sured even when high lines are cast. If ordinary lines are to be cast, the casting mold support k will force back the space rings with the parts d, e, f, g , to the extent a , so that the space rings will be brought into 55 the position according to Figure 3 in which a tight closing will also take place.

Having now particularly described and ascertained the nature of the said invention, and in what manner the same is to be per- 60 formed, I declare that what I claim is:—

1. In a matrix setting and type line cast- 65 ing machine a casting mold, ring spacers, a square spindle carrying the said ring spacers in the line, supports at both ends of the said spindle, guides for said supports and springs located in said guides and acting on the supports.

2. In a matrix setting and type line cast- 70 ing machine, a casting mold, ring spacers, a square spindle carrying the said ring spacers in the line, springs supporting the square spindle against the pressure of the casting mold and allowing a vertical movement of the said square spindle in relation to the 75 said casting mold.

In testimony whereof I affix my signature.
JULIUS DORNETH.
